UNITED STATES PATENT OFFICE.

WILLIAM G. BEATTY, OF FERGUS, ONTARIO, CANADA.

CARRIER.

No. 911,284.

Specification of Letters Patent.

Patented Feb. 2, 1909.

Application filed October 29, 1907. Serial No. 399,765.

To all whom it may concern:

Be it known that I, WILLIAM G. BEATTY, of the town of Fergus, in the county of Wellington and Province of Ontario, Canada, have invented certain new and useful Improvements in Carriers; and I hereby declare that the following is a full, clear, and exact description of the same.

This invention relates to the swivel connection between the lower and upper sections of the carrier, whereby the upper section can be maintained in a fixed position on the track rails to travel in a fixed path thereon, and the lower section can be turned in any desired direction during the lifting or lowering of the bail pulley or the travel of the carrier. To the construction of the carrier lock by which the bail pulley is temporarily fastened to the carrier. To the inclined stop block for positioning the carrier lock when the carrier has reached its loading point.

For a full understanding of the invention reference is to be had to the following description and to the accompanying drawings, in which;

Figure 1 is a perspective view of a section of the track. Fig. 2 is a longitudinal section of the same. Fig. 3 is a transverse section of the track through one of the track clips and washers. Fig. 4 is a transverse section of the track through one of the joint clips and washers. Fig. 5 is a perspective view of the carrier with part of the upper part broken away, showing the carrier lock in its operative position. Fig. 6 is a similar view to Fig. 5, showing the carrier lock in its inoperative position. Fig. 7 is a detail view of the carrier lock and grappling hooks, showing the latter positioned to engage the bail pulley and the former locking them in their holding position. Fig. 8 is a view of the same parts as in Fig. 7, showing the carrier lock positioned to release the grappling hooks. Fig. 9 is a view of the bail pulley sheave, and Fig. 10, is a perspective view of the double inclined cam.

Like characters of reference refer to like parts throughout the specification and drawings.

The track consists of two track rails, each formed of a steel angle bar, with their horizontal flanges *a* adjoining, and located in the same plane but separated by an unoccupied space, and their vertical flanges *b*, arranged in parallel planes. The track rails

are rigidly held in their set position by track clips *c*, located below the horizontal flanges *a*, and provided with clip flanges *d* which engage the outer surfaces of the vertical flanges *b* and prevent the outward lateral displacement of the track rails; and by track washers *e*, located above the horizontal flanges *a* to engage the vertical flanges *b* and prevent the inward displacement of the track rails. Extending through the track clips and track washers are the screw threaded ends *f*, of the track hangers *g*, and adjustable on the screw threaded ends *f*, are clamping nuts *h*, which engage the track clips and washers and clamp them against the bottom and top surfaces respectively, of the horizontal flanges *a*.

As shown in the drawings the track hangers *g*, are of a substantially V-shape, and their screw threaded ends extend through the track clips and track washers intermediate the vertical flanges *b*, there being sufficient clearance between the vertical flanges *b* and the track hangers for the unobstructed passage of the travelers. At the peak of the V-shaped track hanger *g*, is a bracket *i*, comprising an eye part *j*, which encircles the track hanger *g*, and two arms *k* diverging from the eye part to be connected to the rafters or other timbers of the building structure, the angle of the diverging arms *k*, corresponding to the angle of divergence of the rafters or timbers.

At the joints formed by the sections of the track rails, are joint clips *l*, overlapping the joints and extending beneath the adjoining ends of the track rail sections. The joint clips are formed with flanges *m* which engage the outer surfaces of the vertical flanges of the track rails to assist the track clips in preventing the outward lateral displacement of the track rails. Located between the vertical flanges *b*, and alined with the joint clips *l*, are joint washers *o* which engage the horizontal flanges *a* at the adjoining ends of the track rail sections and assist the track washers in preventing the inward lateral displacement of the track rails; and passing through the joint clips and washers are clamping bolts *p*, provided with nuts *q*, by which the joint clips and washers are rigidly clamped against the horizontal flanges *a*. When each section of the track rails, leaves the factory, a joint washer *o* is secured to it by clamping clip *o''* and bolt *o³*

and extends beyond one end thereof, and a joint clip l , is secured to it and extends beyond the other end thereof; so that when a section carrying a joint clip is butted to one carrying a joint washer, the joint washer will overlap the joint clip, and the sections can be bolted together. Thus the person erecting the track has no parts to assemble since the track is complete in itself, and the likelihood of the joint clips and joint washers being mislaid, is obviated.

Traveling on the vertical flanges b , are the travelers r , of the carrier. The travelers r , are arranged in two alined sets, and each traveler is mounted on a stud r'' projecting from the inner face of its respective truck side s . The alined sets of travelers are separated from one another by an unoccupied space so that they will clear the track hangers g , as the carrier moves on the track rails. The truck sides s are provided with slots s'' through which the truck sides are bolted to arms t projecting upwardly from the swivel ring u . By means of the slots s'' and bolts t'' , the truck sides can be adjusted so that all the travelers will engage with the track rails and travel evenly thereon. The swivel ring u , is formed with a flange v projecting from it in a plane at right angles to the plane of the arms t . Suspended from the swivel ring u , is a carrier bell w , having a socket x , for the swivel ring u , and a flange y , to engage with the flange v and revolvably lock the carrier bell thereto. Pivoted to the sides of the carrier bell w , are grappling hooks z , formed at their upper ends with lugs a' , to be engaged by a locking ring b' . The locking ring b' is suspended from the vertical portions of two separated bell crank arms c' pivotally connected to the inner faces of the truck sides s , and formed with stops d' which engage corresponding stops d'' projecting from the inner faces of the truck sides. The pivots for the grappling hooks z , are so positioned that the grappling hooks separate by gravity to receive between them, the bail pulley f' when the locking ring b' is lifted out of engagement with the lugs a' . Each of the grappling hooks z , is formed with an inwardly extending finger g' located in the path of the bail pulley f' , and projecting inwardly from each of the fingers is a pin h' . The pin h' of each finger works in a slot i' in the other finger.

Connected to the track rail opposite the loading place is a double inclined cam j' , which engages inwardly projecting lugs h' formed on the arms c' and raises the arms c' to hold the locking ring b' out of contact with the lugs a' . The carrier bell w , is provided with grooved rope sheaves l arranged on opposite sides of the grappling hooks and alined with the center thereof.

65 The bail pulley sheave consists of a cen-

tral web m' formed with a grooved rim o' which projects beyond each side of the central web m' and extending from each side of the grooved rim o' at the inner face thereof, is a flange p' , to increase 70 the gripping surface for the grappling hooks z . Passing through the central web m' , is a sheave pin q' which is supported in the sides of the sheave casing r' , to which is swiveled a sling hook s' . The sides of the 75 sheave casing r' are formed with semi-circular flanges a'' which register with the outer surfaces of the flanges p' . The lifting rope t' passes over one of the rope sheaves l' , under the bail sheave f' and over the other rope 80 sheave l' , so that the lifting rope will raise the sheave of the bail pulley into engagement with the grappling hooks. When the carrier approaches the loading point, the cam j' engages the lugs h' , oscillates the arms c' and 85 raises the locking ring b' out of engagement with the lugs a' , and the grappling hooks z , then open by gravity so that the sheave of the bail pulley f' can enter between them. When the lugs h' pass the cam j' the locking 90 ring descends and rests on the top of the lugs a' . When the bail pulley f' is raised by the lifting rope t' the bail pulley sheave engages the fingers g' and causes the grappling hooks z to close beneath the flanges q' and rim o' . 95 This movement of the grappling hooks causes the lugs a' to separate and the locking ring b' then enters between them and holds the lugs separated to cause the grappling hooks z to remain in engagement with the 100 bail pulley sheave until the carrier has completed its travel on the trackway and returned to the loading point where the cam j' again engages the lugs h' and lifts the locking ring b' into an inoperative position so 105 that the grappling hooks can separate and disengage themselves from the bail pulley sheave.

Having thus fully described my invention what I claim as new and desire to secure by 110 Letters Patent is:

1. A carrier comprising two truck frame sides, a swivel ring, arms extending from the swivel ring and engaging the truck frame sides, means adjustably fastening the 115 arms and truck frame sides together and a carrier bell connected to the swivel ring.

2. A carrier comprising two truck frame sides, a swivel ring, arms extending from the swivel ring and engaging the truck 120 frame sides, means adjustably fastening the arms and truck frame sides together, a carrier bell connected to the swivel ring, grappling hooks for the carrier bell and travelers for the truck frame sides.

3. A carrier comprising two truck frame sides, a swivel ring, arms extending from the swivel ring and engaging the truck frame sides, means adjustably fastening the 125 arms and truck frame sides together, a car-

rier bell connected to the swivel ring, slots in the truck frame sides and bolts passing through the slots and arms.

4. A carrier comprising a truck frame, a carrier bell revolubly connected to the truck frame, grappling hooks pivoted to the carrier bell, lugs formed at the upper ends of the grappling hooks, a locking ring to enter between the lugs and engage therewith, and arms pivotally connecting the locking ring to the truck frame.

5. A carrier comprising a bail pulley sheave consisting of a central web, a grooved rim for the web projecting beyond each side thereof, a flange extending laterally from each side of the rim at the inner surfaces thereof and a casing for the bail pulley sheave having a flanged part registering with the flanges of the sheave rim.

6. A carrier comprising a truck frame, a carrier bell revolubly connected to the truck frame, grappling hooks pivotally connected to the carrier bell and inwardly extending fingers for the grappling hooks.

7. A carrier comprising a truck frame, a carrier bell revolubly connected to the truck frame, grappling hooks pivotally connected to the carrier bell, lugs for the grappling hooks and a locking ring to engage with the lugs.

8. A carrier comprising a truck frame, a carrier bell revolubly connected to the truck frame, grappling hooks pivotally connected to the carrier bell, inwardly extending fingers for the grappling hooks, lugs for the grappling hooks and a locking ring to engage with the lugs.

9. A carrier comprising a truck frame, a carrier bell revolubly connected to the truck frame, grappling hooks pivotally connected to the carrier bell, inwardly extending fingers for the grappling hooks, said fingers having guide slots and pins working therein.

Fergus, Ontario, October 17th A. D. 1907.
